CLOSURE FOR RECEPTACLES

William M. Moxley, Kansas City, Mo.

Application January 6, 1941, Serial No. 373,355

3 Claims. (Cl. 220—55)

This invention relates to a closure for containers. It is of particular utility as a closure for the tops of the bodies of lanterns of the character of that shown in my U. S. Patent 2,096,349 issued October 19, 1937.

It is a primary object of the invention to provide a cover or closure having locking means of such a nature that by a partial rotation of a conveniently located and shaped hand-grasp element, a plurality of bolts may be, simultaneously, retracted to release the closure or projected to secure the closure in place upon the lantern body or other receptacle. Springs are associated with the bolts, positioned to act by a "past center" thrust to hold the bolts in either the retracted or projected position. The several parts of the closure are so correlated that the closure, hand-grasp element, bolts, springs and actuating means for the bolts are held in assembled relation as a unit and without the possibility of the bolts dropping out of proper position even when the closure, as a whole, is removed from the body.

Further objects and advantages of the invention will be set forth in the detailed description which follows.

In the accompanying drawing:

Figure 1 is a view partly in side elevation and partly in vertical section of a portion of a lantern body having the closure of the present invention applied thereto;

Fig. 2 is a fragmentary plan view of one of the bolts showing the same in retracted position;

Fig. 3 is a horizontal, sectional view upon line 3—3 of Fig. 1 showing the bolts in projected or locking position;

Fig. 4 is a plan view of the hand-grasp element hereinafter described, and,

Fig. 5 is a plan view of the cover of the closure for the container.

Like numerals designate corresponding parts throughout the several figures of the drawing.

In the drawing 5 designates any suitable container, such, for example, as an electric lantern body. When used as a lantern body the receptacle may be provided with any suitable form of bail 6. A cover plate or closure 7 is shaped to fit snugly upon the top edge of the body 5 and carries a plurality of downwardly projecting ears 8.

A hand-grasp disc or plate 9 adapted to be turned in a horizontal plane with relation to cover 7, is secured by suitable rivets 10 to a bolt actuating eccentric 11, it being noted that these

rivets pass through a hub-like projection 12 of the plate 9, which hub fits and has a bearing in a central opening 13 of the cover 7. Pins or rivets 14 are fixed at their upper ends in plate 9 and at their lower ends to the eccentric 11, while their intermediate portions are free to have a limited travel in arcuate slots 15 of the cover 7. Thus the hand-grasp plate 9 and the eccentric 11 may be given a partial rotation with respect to the cover 7 and this partial rotation is utilized to actuate locking bolts 16.

The inner ends of these bolts are pivotally connected at 17 to a horizontal flange 18 which constitutes a part of the eccentric 11, while the outer ends of the bolts are slidably disposed in the ears 8. Springs 19 bear between the ears 8 and washers 20 which lie adjacent the pivots 17.

When the hand-grasp element is turned in one direction to the limit of its movement as determined by the length of the arcuate slots 15, the bolts are retracted to the position illustrated in Fig. 2 and the closure may be lifted off of the receptacle 5, while when the said element is turned to the limit of its movement in the other direction the bolts will be projected outwardly through ears 8 to pass through the wall of receptacle 5.

The ends of the bolts are preferably beveled as indicated at 21 so that during their projection they exert a cam action to draw the cover 7 snugly upon receptacle 5. When used as a lantern body a spring 22 may be secured to the underside of the eccentric in position to engage the dry cell 23 of the battery or to engage a connecting bar between the dry cells in batteries employing more than one cell. In either case the drawing action exerted by the beveled ends of the bolts 21 increases the tension upon the spring 22.

It should be noted that the construction illustrated lends itself to use with receptacles of other than circular form. The cover could be applied just as readily to an oval or oblong or square receptacle, it being only necessary to vary the length of the bolts in order to take care of different shapes.

The parts are of such a nature that most of them may be readily stamped out at a small cost. It will be seen that the plate 9, cover 7, eccentric 11, ears 8 and bolts 16 are all united in such a way that they remain a unitary structure during the placement or removal of the closure. Many of the lantern bodies now on the market utilize covers having either a mere slip engagement or a screw engagement with the lantern body. While

covers of that nature work satisfactorily when the devices are new, the least exposure to unfavorable weather conditions results in such rusting and corrosion as to make it very difficult, if not impossible, to get the covers on or off.

The present invention provides a closure in which the hand-grasp element is of such size and exerts such power with respect to the locking bolts as to make it easy to manipulate the parts under all conditions of use, while at the same time insuring that the cover will remain locked or unlocked under the "past center" thrust of the springs at the opposite limits of movement of the eccentric 11.

It is to be understood that the invention is not limited to the precise construction set forth, but that it includes within its purview whatever changes fairly come within either the terms or the spirit of the appended claims.

Having described my invention, what I claim is:

1. A device of the character described, comprising a closure plate, a hand-grasp element journaled to turn with respect to said plate, a bolt actuating member secured to the hand-grasp element and located beneath the closure plate and having an out-turned longitudinal flange which constitutes its outer edge, a receptacle upon which the closure plate fits, a plurality of bolts pivoted at their inner ends to said flange and adapted to be projected or retracted by rotation of said member with respect to the closure plate, depending ears carried by the closure plate and adapted to fit within the receptacle, and within which the outer ends of the bolts are slidably disposed, there being openings in the side walls of the receptacle for the reception of the outer ends of said bolts when said bolts are projected, compression springs bearing between the depending ears and the pivot points of said bolts, the dimensions, relationship, and throw of the named parts being such that said springs are under greatest compression when the bolts are radially disposed with respect to the closure plate and are farthest projected, and means for limiting the throw of the hand-grasp

element with respect to the cover plate in such manner that the pivot points of the bolts will lie in past center position at each of said limits of movement.

5 2. A device of the character described, comprising a receptacle, a closure plate shaped to fit upon and to close said receptacle, said plate having a central opening formed therethrough, a hand grasp element overlying the closure plate and having a hub-like portion which projects through the closure plate and which serves to journal the hand grasp portion in the closure plate, a circular member secured to the underside of said hub-like portion and of a diameter to overlap the closure plate, pins traversing said member and the hand grasp element, said pins passing through arcuate slots formed in the closure plate, whereby movement of the hand grasp element with respect to the closure plate is limited in both directions, said circular member having an outwardly projecting flange around its lower edge, a plurality of bolts, means for pivoting the inner ends of said bolts to said flange, depending members carried by the closure plate and fitting within the receptacle in close engagement with the wall of said receptacle, said bolts passing through openings formed in said members, there being openings in the wall of the receptacle for the reception of the outer ends of said bolts when said bolts are projected, compression springs surrounding the bolts and bearing between the depending members and the pivot points of said bolts, said bolts having their outer ends beveled to coact with the walls of the openings of the receptacle to exert an inward drawing action upon the closure plate, as said bolts are thrust into said openings.

3. A structure as recited in claim 2, in combination with a battery to be retained in said receptacle and a spring bearing between the end of said battery and the underside of said circular member, the action of the beveled ends of the bolts tending to increase the tension upon said spring as the closure plate is drawn toward the receptacle.

WILLIAM M. MOXLEY.
